Primary Examiner — Richard E Chilcot

(57) **CLAIM**

The ornamental design for an exercising apparatus, as shown and described.

DESCRIPTION

1. Exercising apparatus

1.1 : Top

1.2 : Bottom

1.3 : Back

1.4 : Front

1.5 : Left

1.6 : Right

1.7 : Perspective

1.8 : Perspective

1.9 : Perspective

The parts shown by means of broken thick lines in the reproductions are not part of the claimed design; the thin lines on the surfaces of the product in the reproductions

(Continued)

represent contours only and do not illustrate an ornamentation or decoration on the surface of the product.

1 Claim, 9 Drawing Sheets
